UNITED STATES PATENT OFFICE.

LUCIEN EMILE THÉODORE PERRIN, OF PARIS, FRANCE.

INSULATING UNIT FOR ELECTRIC SUSPENSION-CHAINS.

1,391,576.

Specification of Letters Patent. Patented Sept. 20, 1921.

Application filed October 22, 1920. Serial No. 418,864.

(GRANTED UNDER THE PROVISIONS OF THE ACT OF MARCH 3, 1921, 41 STAT. L., 1313.)

To all whom it may concern:

Be it known that I, LUCIEN EMILE THÉODORE PERRIN, a citizen of the French Republic, of 41bis Rue de Châteaudun, Paris, France, has invented new and useful Improvements in Insulator Units for Electric Suspension-Chains, (for which I have filed applications in France August 1, 1919, Patent No. 516,996 and in France October 2, 10 1920,) of which the following is a specification.

The subject of the present invention is an insulator unit for use in the composition of electric suspension chains for high tension lines.

The metal which enters into the fabrication of the other devices of this kind at present in use, and which is always detrimental, is avoided in the construction of the 20 insulator unit hereafter to be described, and the assembling of the several units composing a chain is effected by the simple process of screwing, no sealing being necessary.

In the annexed drawings—

25 Figure 1 shows an elevation and part section of an insulator unit constructed according to the present invention.

Fig. 2 shows the manner in which several such units may be assembled to form a suspension chain.

30 Fig. 3 is a sectional view of a unit taken on line 3—3 of Fig. 1.

The insulator unit (Fig. 1) is composed of an insulator of porcelain 1 of suitable 35 shape. In the lower part of this insulator is a cavity 2 the sides of which are fitted with a screw thread and the bottom curved out in the shape of a segment of a sphere. Inside the cavity 2 is screwed a sleeve 3 made 40 of some strong, non-conducting material. The lower part of the insulator sleeve 3 is provided with a rectangular hole 4. An insulator stem 5, also made of some non-conducting material of sufficient mechanical 45 strength passes through the hole 4 and terminates in a spherical insulator ball 6 which rests on the sleeve 3 in such a way that it is able to oscillate inside the cavity 2 into which it fits. The stem 5 is finished at the 50 lower end by a screw thread 7 on the outside, while the upper part of the porcelain insulator 1 is fitted on the inside with a screw thread 8 which, when the insulator units forming the chain are assembled, receives

the screwed end of the stem of the unit immediately above it. 55

The object of the rectangular hole 4 is to allow the sleeve 3 to be screwed into the cavity 2 of the insulator 1 by means of a special spanner. Moreover, a hole 14 in the sphere 6 allows for the screwing or unscrewing, with a suitable tool, of the stem 5 in the cavity 8 of the insulator situated immediately below. This hole may be placed to equal advantage anywhere else on the stem 5. 65 It will thus be seen that the fitting together and assembling of the various units are conducted with the utmost ease and rapidity.

It may be pointed out that with this method of assembling the insulator parts 70 with the porcelain parts no space is left in which air or water might find a refuge; all the parts are screwed solid, leaving only just the play necessary for the insulator ball inside the porcelain to oscillate freely. 75

Fig. 2 represents a suspension chain formed of insulator units similar to those described above.

The principal part of the chain, *i. e.*, that part comprised between the points 9 and 10, 80 is composed of insulator units and contains no metal. At the top of the chain an insulator stem 11 is screwed to the upper part of the first porcelain insulator and connects the chain to a metal spherical ball joint 12 85 by one of the usual devices. In the same way the lower part of the stem 5 of the last insulator unit connects the chain in the usual manner to a metal spherical ball joint 13. 90

It should be observed that the method of fitting described above may be applied to any type of suspension chain used on high tension lines; the shape of the porcelain insulator alone varies according to the position 95 the chain is intended to occupy on the high tension line (running chains, dead endings, curved chains, etc.).

It is to be noted that in the above described case, the porcelain is submitted to 100 tension, but of course the invention could be applied to any form of insulator unit which would be submitted to compression strains.

What I claim is:

1. Insulator unit for electric suspension chains on high tension lines comprising a porcelain part, a cavity in the lower end

- of this part, a sleeve made of some non-conducting material of great mechanical strength inside this cavity, a rectangular hole in the lower part of the sleeve, a stem made of the same nonconducting material as the sleeve the lower end of which is threaded while the upper end passes through the said rectangular hole, a spherical ball made of the same nonconducting material as the stem at the top of said stem and resting on the 30 said sleeve inside the said cavity, and a cavity in the top of the porcelain part fitted with a screw thread of the same diameter as the said stem.
- 10 the stem at the top of the said stem and resting on the said sleeve inside the said cavity, and a cavity in the top of the porcelain part fitted with a screw thread of the same diameter as the said stem.
- 15 2. Insulator unit for electrical suspension chains on high tension lines comprising a porcelain part, a cavity in the lower end of this part, a screw thread inside this cavity, a sleeve made of some nonconducting material of great mechanical strength inside the said cavity, a screw thread on the outside of this sleeve corresponding to the screw thread inside the cavity, a rectangular hole in the lower part of the sleeve, a stem made 20 of the same nonconducting material as the
- 25

sleeve the lower end of which is threaded while the upper end passes through the said rectangular hole, a spherical ball made of the same nonconducting material as the stem at the top of said stem and resting on the 30 said sleeve inside the said cavity, and a cavity in the top of the porcelain part fitted with a screw thread of the same diameter as the said stem.

3. An insulator unit for electrical suspension chains on high tension lines comprising a porcelain part having a cavity in its lower end, a sleeve of non-conducting material secured in said cavity, and a stem of non-conducting material having a threaded lower 40 end and a spherical ball at its upper end, the ball being located in the cavity and resting on said sleeve and the stem passing through said sleeve, the upper end of the porcelain part being provided with a cavity having a 45 threaded wall designed to engage the threaded stem of another unit.

In witness whereof I have hereunto set my hand.

L. PERRIN.
